Primary Examiner — Thomas Johannes*Assistant Examiner* — Lauren McVey(74) *Attorney, Agent, or Firm* — Alexander D. Raring(57) **CLAIM**

The ornamental design for a toaster oven, as shown and described.

DESCRIPTION

FIG. 1 is a top, front and right side perspective view of a toaster oven, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines immediately adjacent the shaded areas represent the bounds of the claimed design while all other broken lines are directed to environment and are of illustrative purposes only; the broken lines form no part of the claimed design.
